FIG.5

FIG.1

FIG. 2

FIG. 3

FIG. 1 is a perspective view taken from the top and one side of a riding lawn mower showing our new design;

FIG. 2 is a perspective view taken from the top and side opposite to that shown in FIG. 1;

FIG. 3 is a front perspective view thereof;

FIG. 4 is a rear perspective view thereof; and

FIG. 5 is an enlarged fragmentary view of the rear ground engaging roller of the riding lawn mower illustrated in FIGS. 1, 2, 3 and 4.

The dominant features of our design reside in the full line portion of the drawings.

We claim:

The ornamental design for a riding lawn mower, substantially as shown and described.
